UNITED STATES PATENT OFFICE.

STANLEY S. MORRIS, OF NEW ORLEANS, LOUISIANA.

DESIGN FOR A COMBINATION CLOCK STAND AND PAD SUPPORT.

Application filed June 9, 1922. Serial No. 2,603. Term of patent 7 years.

To all whom it may concern:

Be it known that I, STANLEY S. MORRIS, a citizen of the United States, residing at New Orleans, in the parish of Orleans and State of Louisiana, have invented a new, original and ornamental Design for a Combination Clock Stand and Pad Support, of which the following is a specification, and illustrated in the accompanying drawing, forming a part thereof, wherein—

Figure 1 is a view in elevation of a com-

bination clock stand and pad support showing the new design.

Figure 2 is a perspective view of the same.

I claim:—

The ornamental design for a combination clock stand and pad support as shown.

STANLEY S. MORRIS.
